[57] CLAIM

The ornamental design for a cell insert for a tissue culture plate, as shown and described.

DESCRIPTION

FIG. 1 is a top and front perspective view of the cell insert for a tissue culture plate;

FIG. 2 is a top plan view thereof;

FIG. 3 is a front elevational view thereof;

FIG. 4 is a side elevational view thereof;

FIG. 5 is a bottom elevational view thereof; and,

FIG. 6 is a cross-sectional view thereof, taken along the line 6—6 of FIG. 2.

FIG-1

FIG-2

FIG-3

FIG-4

FIG-5

FIG-6
